CHANNELIZED HIGH-FREQUENCY SIGNAL RECEIVING SYSTEM

Frank M. Davis, Cedar Rapids, Iowa, assignor to
 Collins Radio Company, Cedar Rapids, Iowa, a
 corporation of Iowa

Application November 21, 1945, Serial No. 629,991

7 Claims. (Cl. 250—20)

1

This invention relates to wave signalling systems and more especially to radio receivers adapted to operate over a large number of receiving frequency channels.

A principal object of the invention is to provide a multi-channel radio receiver having a plurality of successive crystal stabilized stages operating at different carrier frequencies, and wherein the total number of crystals required for all frequencies is a minimum but without sacrificing overall frequency stability.

Another object is to provide a radio receiver of the plural heterodyne type wherein successive heterodyne stages are frequency-stabilized by a common group of crystals each crystal simultaneously controlling the frequency of the successive stages.

Another object is to provide a radio receiver of the double superheterodyne type employing a succession of frequency converters for lowering a received radio carrier to successively lower frequency ranges, the converters being stabilized by a single bank of piezo crystals under control of a switching arrangement so that each crystal serves to stabilize simultaneously a plurality of successive stages.

A further object is to provide a radio receiving system for operation on a large number of frequency-stabilized reception channels employing a minimum number of stabilizing elements such as piezo crystals, while maintaining the channels accurately positioned and equally spaced throughout the frequency spectrum for which the system is designed.

A feature of the invention relates to a radio receiver of the double superheterodyne type wherein the local oscillators for the successive frequency conversion stages are controlled by a common bank of piezo crystals, the crystals being switched into circuit with the respective local oscillators in a predetermined order and in accordance with the particular channel at which the receiver is tuned for operation.

A still further feature relates to the novel organization, arrangement and relative interconnection of parts which cooperate to provide a stable and economical crystal-controlled multi-channel frequency conversion system having a plurality of successive frequency conversion stages.

Other features and advantages not particularly enumerated will be apparent after a consideration of the following detailed descriptions and the appended claims.

In present day radio systems, for example in

2

radio receivers, it is highly desirable to be able to operate the system over any one of a comparatively large number of frequency channels. In order to achieve this objective, it has been found necessary to insure that the respective channels are stabilized at their respective frequencies, and should preferably be of equal frequency width. It is also desirable that the channels be accurately selectable with a minimum of tuning and selecting adjustments. When such systems operate at the same carrier frequency throughout successive stages, or where a single frequency conversion stage is employed, the problem is relatively simple since the same frequency stabilizing elements e. g. 5 a piezo crystal, can be used for all stages which operate at the same carrier frequency. If, however, the system employs a series of successive stages operating at different carrier frequencies, e. g. different frequency conversion stages as in 10 the case of a double superheterodyne receiver, the problem of stabilizing the overall system becomes relatively complex. In accordance with the present invention it is possible to employ a single bank of frequency stabilizers such as piezo crystals 15 for conjoint use for successive stages operating at different frequency conversions. This greatly simplifies the tuning and channel selecting operations in the use of the system, and greatly reduces the cost and space requirements 20 for the apparatus.

Merely for simplicity in explaining the inventive concept and one particular mode of practicing it, there is shown in block diagrammatic form a radio receiving system in which the invention is incorporated. It will be understood that in certain of its phases the invention is not limited to a radio receiver, and is also applicable to any wave signalling system employing a plurality of successive frequency conversion stages all of which 25 are to be crystal stabilized.

Referring to the single figure of the drawing, there is shown a receiving antenna or radiation pick-up device 1 which is connected to a tunable preselector 2 which may take the form of a tunable radio frequency amplifier of any known kind. Amplifier 2 is adapted to be tuned over a comparatively wide band sufficient to cover all the frequency channels at which the system can be 35 operated. The device or devices for effecting this tuning are indicated by the arrow 3 and may comprise one or more amplifier stages all the tuning elements of which are ganged together for unitary tuning control. Merely for explanation, the 40 amplifier 2 may be designed to amplify uniformly 50 55

and efficiently received carrier frequencies over the range 108 to 118 megacycles.

The amplified waves from device 2 are applied to a mixer or frequency converter stage 4 which may take the form of any well-known frequency converter tube such as conventionally used in the frequency conversion stage of a superheterodyne radio receiver. There is also applied to the mixer 4 a local oscillator beat frequency which is generated by the local oscillator 5 which may be of any well-known electron tube type having an adjustable frequency-determining or tuning element which is schematically illustrated by the arrow 6. Oscillator 5 is of the type which is stabilized at its selected or tuned frequency by means of a particular one of the series of piezo crystals 7 to 16. The frequencies from oscillator 5 are multiplied in frequency by any well-known frequency multiplier 17 whereby the actual beat frequency applied to mixer 4 is ten times the frequency of the selected crystal. For example, crystal 7 may have a frequency of 9.5 megacycles and each of the succeeding crystals may have a frequency which is 0.1 megacycle greater than the preceding crystal. The respective crystal frequencies are indicated in the drawing by the frequencies adjacent each of their respective conductors which are connected to corresponding stationary contacts in the contact bank of a rotary switch 18. The rotatable brush 19 of this switch can therefore select any desired one of the crystals for connection to the oscillator 5.

As indicated by the dotted line connections, the tuning elements 3, 6, and the brush 19 are ganged together to a common tuning indicator dial 20 so that tuning of the amplifier 2 to any desired frequency channel in the band 108 to 118 megacycles, automatically connects the proper crystal in circuit and automatically tunes the oscillator 5 to the corresponding channel frequency.

In the drawing the numerals above the respective blocks, represent a particular selected spot frequency, while the numerals below the respective blocks indicate the respective frequency bands. The ganging of the various elements 3, 5 and 19 is such that the resultant beat frequency in the output of mixer 4 is confined to the band 13 to 13.9 megacycles, it being understood that the filter 21 is of the band pass type to cover the 13 to 13.9 megacycle band. The device 21 may be of any well-known band pass type and may, if desired, include a corresponding band amplifier.

The signals from device 21 are then applied to another mixer or frequency converter 22 which in turn is supplied with a local beat frequency from the local oscillator 23. Oscillator 23 is provided with a tuning element 24 so that the oscillator can be tuned over the band 9.5 to 10.4 megacycles as is the oscillator 5 already described. The oscillator 23 is of the crystal stabilized type and is connected to the rotary brush 25 of a switch whose stationary bank contacts are multiplied to the respective crystals 7 to 16. The brush 25 and the tuning element 24 are ganged through a suitable gearing or ratio coupling 26 to the dial 20 so that for each tenth of a turn of the dial 20 the brush 25 makes a complete revolution, it being understood that the previously described brush 19 is ganged to the dial 20 so that brush 19 makes a complete revolution for each complete revolution of dial 20. In other words, the received band of 108 to 118 megacycles may be considered as divided into 100 separate frequency

channels, each channel having a width of approximately 0.1 megacycle. When the tuning element 3 is tuned to any channel between 108 and 108.9 megacycles the brush 19 is in engagement with stationary contact 27. When the tuning element 3 is tuned to the band 109 to 109.9, brush 19 is advanced into engagement with the next stationary contact 28, and so on for the remaining frequency channels. However the brush 25 is geared in a ten to one ratio to the brush 19. Thus, when the element 3 is tuned to the 108 megacycle frequency, brush 25 is in engagement with stationary contact 29. As the device 3 is tuned over the band 108 to 108.9 megacycles, the brush 25 makes ten successive steps corresponding to each of the ten frequency channels in the 108 to the 108.9 band. With this ganging arrangement, the beat frequency in the output of mixer 22 is confined to a particular intermediate frequency, and in the system as illustrated this intermediate frequency is 3.5 megacycles which is applied to a corresponding I. F. amplifier 30 whose output is applied to any well-known detector 31 for detecting the signal modulations in the amplified I. F. carrier. These signal modulations can then be applied to any well-known audio frequency amplifier 32 whose output is connected to any suitable signal reproducer 33.

In the particular example illustrated in the drawing, it is assumed that the system is to receive on the channel 109.9 megacycles. Under these conditions the dial 20 is turned so that the element 3 tunes the amplifier 2 to 109.9 megacycles. Since this desired channel is in the second decade, the turning of dial 20 automatically advances the brush 19 to the second stationary contact 28 thereby connecting crystal 8 in circuit and causing a local beat frequency of 96 megacycles to be applied to mixer 4. The difference frequency of 13.9 megacycles is then amplified in the band pass amplifier 21 and is applied to the mixer 22. At the same time since the desired channel is in the ninth subdivision of the second decade frequency range, the adjustment of dial 20 as above described causes brush 25 to be advanced to the ninth stationary contact 34, thus connecting the 10.4 megacycle crystal 16 in circuit with oscillator 23. There is thus produced an intermediate beat frequency of 3.5 megacycles which is suitably amplified in the amplifier 30.

If desired, the brush 25 and the tuning element 24 of oscillator 23 can be independently adjusted so that they are not ganged to the dial 20. Under that condition there would be provided two tuning knobs or dials, namely the dial 20 and another dial which controls the brush 25 and the oscillator tuning element 24. The dial 20 would then be calibrated in one megacycle steps, and the dial for oscillator 23 would be calibrated in ten steps from 0.1 megacycle to 0.9 megacycle.

While one particular frequency conversion system and while one particular band of frequency channels have been described, it will be understood that changes and modifications may be made therein without departing from the spirit and scope of the invention.

What is claimed is:

1. A radio receiving system of the type adapted to receive on a plurality of selectable input carrier frequencies the frequencies being divisible into "X" groups and with "Y" frequencies in each group, a plurality of successive frequency converter stages of the superheterodyne type for the received carrier frequencies, means selectively to

supply one stage with any desired one of "X" local beating oscillations, means selectively to supply the succeeding stage with any desired one of "Y" beating oscillations of different frequencies from those supplied to the first stage, a bank of piezo crystals the number of crystals being equal to "X" and each crystal being capable of simultaneously stabilizing the local beating oscillations of both said stages, a plurality of switches each switch having a set of bank contacts and a selectively movable brush, said crystals being connected in multiple to the bank contacts of each switch, and said brushes being individually connected to the corresponding local oscillator generator for each of said stages, to enable a single crystal to simultaneously stabilize both said stages and to enable any desired combination of crystals to be connected to said stages to simultaneously stabilize their respective frequencies.

2. A radio receiver of the double superheterodyne type to receive on any one of a plurality of selectable input frequencies and comprising a pair of successive frequency conversion stages, means including an oscillator generator to supply one stage with local beating oscillations, means including another oscillator generator to supply the preceding stage with local beating oscillations whose frequencies are multiples of the first-mentioned beating oscillations, a plurality of piezo crystals, each crystal being connectable simultaneously to both said generators to stabilize their respective frequencies, a multi-point switch for connecting a selected one of said crystals to the first-mentioned oscillator generator, another multi-point switch for connecting said selected crystal or any other one of said crystals to the second-mentioned oscillator generator and thereby maintaining the converted frequency from said one stage uniform, regardless of the frequency to which the receiver is tuned.

3. A radio receiver according to claim 2 in which each of said switches includes a set of fixed contacts one for each crystal, the fixed contacts in both switches being connected in multiple to said crystals for connecting them in different combinations to said oscillator generators.

4. A radio receiving system of the type adapted to receive a plurality of selectable input carrier frequencies, a plurality of successive frequency converter stages of the superheterodyne type for the received carrier frequencies, means including an oscillator-generator to supply one stage with local beating oscillations, means including another oscillator-generator to supply a succeeding stage with local beating oscillations of a frequency different from the first-mentioned beating oscillations, means to tune each oscillator to a plurality of beating frequencies, a single bank of piezoelectric crystals common to both said oscillators, and switching means for connecting any one of said crystals to both oscillators to control both oscillators simultaneously, and also for connecting said crystals in different combinations respectively to said oscillators and thereby to maintain the converted frequency of said succeeding stage constant, for any one of said selected input frequencies.

5. A radio receiver of the double superheterodyne type having an input radio frequency amplifier selectively tunable to any one of a series of carrier frequency channels, a first frequency converter which is connected to the output of said amplifier, a source of local beating oscillations for said first converter and including a

crystal-controlled tunable oscillator which is connected to said first converter through a frequency multiplier, a second frequency converter which is connected to the output of said first converter to produce a final intermediate frequency, a second source of local beating oscillations for said second converter and including another tunable crystal-controlled oscillator which is connected to said second converter, a single bank of piezo-crystals for controlling both said local oscillators, a first multi-point switch for selectively connecting any one of said crystals to the first-mentioned local oscillator, and a second multi-point switch for connecting any one of said crystals to the second local oscillator and thereby to maintain the intermediate frequency from said second converter constant, over the entire tuning range of said amplifier.

6. A radio receiver, comprising a tunable input radio frequency amplifier, a first frequency converter connected to the output of said amplifier, a band-pass filter connected to the output of said converter for selecting one side band of the converted frequencies, a second frequency converter connected to the output of said filter to produce an intermediate frequency, an amplifier and detector for said intermediate frequency; a first local beating oscillator for said first converter and having a tuning element for tuning the said first oscillator over a predetermined frequency range of frequencies, another local beating oscillator for said second converter having a tuning device for tuning said second oscillator over the same frequency range as the first oscillator, a frequency multiplier connected between the first local oscillator and the first converter, a bank of piezoelectric crystals common to both said oscillators each crystal being allotted to a corresponding one of the carrier frequency channels to be received and covering the same frequency range as said oscillators, a multi-point switch having a movable contact arm and stationary contacts each connected to a respective crystal for selectively connecting any one of said crystals to the first local oscillator, another multi-point switch having a movable contact arm and stationary contacts each connected to a respective crystal for selectively and simultaneously connecting said selected crystal or any other one of said crystals to the second local oscillator, and means connecting the movable contact arm of the first switch to the tuning element of said first oscillator and to the tuning element of said radio frequency amplifier to tune said amplifier to any desired frequency channel and also for automatically connecting the proper crystal in circuit with the first local oscillator and thereby maintaining the frequency from said intermediate frequency constant, for every carrier frequency channel to be received.

7. A radio receiver of the double superheterodyne type, comprising an input radio frequency amplifier tunable to group and unit frequencies, a first frequency converter connected to the output of said amplifier, a second frequency converter connected to the output of said first converter to produce a final intermediate frequency, a first local beating oscillator for the first converter, a second local beating oscillator for the second converter, each of said oscillators having frequency-adjusting means for maintaining said intermediate frequency constant over the entire tuning range of said amplifier, means to multiply the frequency of the oscillations from the first local oscillator before applying them to

the first converter, each of said local oscillators being of the piezo crystal-controlled type, a bank of piezoelectric crystals connectable to said oscillators for controlling their respective frequencies, the number of crystals in the bank being equal in number to the number of group frequencies to which the said radio frequency amplifier can be tuned, and a pair of multi-point switches one for each of said oscillators for connecting said crystals in different combinations respectively to 10 said oscillators to maintain said intermediate frequency uniform, over the entire tuning range of said amplifier.
